US0D1054010S

(12) **United States Design Patent** (10) **Patent No.:** **US D1,054,010 S**
(45) **Date of Patent:** **** Dec. 10, 2024**

(54) **PORTABLE FAN**

(71) Applicant: **Xiaoxuan Ma**, Guangdong (CN)

(72) Inventor: **Xiaoxuan Ma**, Guangdong (CN)

(**) Term: **15 Years**

(21) Appl. No.: **29/953,294**

(22) Filed: **Jul. 20, 2024**

(30) **Foreign Application Priority Data**

Jan. 23, 2024 (CN) 202430043316.3

(51) **LOC (14) Cl.** **23-04**

(52) **U.S. Cl.**

USPC **D23/381**; D23/370

(58) **Field of Classification Search**

USPC D23/332, 355, 370, 380, 381, 382

CPC F04D 25/084; F04D 25/0673; F04D 29/00

See application file for complete search history.

(57) **CLAIM**

The ornamental design for a portable fan, as shown and described.

DESCRIPTION

FIG. 1 is a perspective view of a portable fan showing the new design;

FIG. 2 is another perspective view thereof;

FIG. 3 is a front elevation view thereof;

FIG. 4 is a back elevation view thereof;

FIG. 5 is a left-side view thereof;

FIG. 6 is a right-side view thereof;

FIG. 7 is a top plan view thereof; and,

FIG. 8 is a bottom plan view thereof.

The broken lines depict portions of the portable fan that form no part of the claimed design.

1 Claim, 8 Drawing Sheets
